UNITED STATES PATENT OFFICE

112,752

DESIGN FOR A FINGER GUARD

Osmer M. Douglas and Maggie Holden,
Salt Lake City, Utah

Application August 5, 1938, Serial No. 79,139

Term of patent 14 years

To all whom it may concern:

Be it known that we, Osmer M. Douglas and Maggie Holden, citizens of the United States, residing at Salt Lake City, in the county of Salt Lake and State of Utah, have invented a new, original, and ornamental Design for a Finger Guard, of which the following is a specification, reference being had to the accompanying drawing, forming part thereof.

Figure 1 is a top plan view of a finger guard, showing our new design.

Figure 2 is a view in side elevation thereof.

Figure 3 is an end elevational view.

We claim:

The ornamental design for a finger guard, as shown.

OSMER M. DOUGLAS.
MAGGIE HOLDEN.
